WRENCH

Filed June 12, 1928

Inventor

W. Monteney,

By Clarence O'Brien, Attorney

UNITED STATES PATENT OFFICE

WARD MONTENEY, OF CASTLE ROCK, WASHINGTON

WRENCH

Application filed June 12, 1928. Serial No. 284,822.

The present invention relates to improvements in wrenches, and has for its principal object to provide a means for adjusting the movable jaw with respect to the stationary jaw in order to accommodate objects of different sizes, means being provided for positively holding the movable jaw in any adjusted position to prevent slipping of the same, while the wrench is in use.

10 A further object is to provide a wrench of the above mentioned character which is simple in construction, inexpensive, strong and durable and further well adapted to the purpose for which it is designed.

15 Other objects and advantages of the invention will become apparent from the following description when taken in connection with the accompanying drawing.

In the accompanying drawing wherein like 20 reference characters indicate corresponding parts throughout the same:

Figure 1 is a side elevation of the wrench embodying my invention.

Figure 2 is a sectional view taken approximately on the line 2—2 of Figure 1 looking in the direction of the arrows, and

Figure 3 is a similar section taken on the line 3—3 of Figure 1 looking in the direction of the arrows.

30 In the drawing wherein for the purpose of illustration is shown the preferred embodiment of my invention, the numeral 1 designates a substantially rectangular shaped shank that is formed at one end with the stationary jaw 2 having gripping teeth formed on the inner face of one end portion thereof as shown at 3. The other end portion of this jaw that projects beyond the inner side edge of the shank 1 is formed with a hammer head 40 4 whereby the wrench may be used as a hammer when so desired. The inner side edge of the shank is formed with the teeth 5 and the purpose thereof will be presently described in detail.

45 A sleeve like member 6 is slidable on the shank 1, and the intermediate portion of this sleeve-like member is cut out at its outer side, as indicated at 7. Formed on one end of this sleeve-like member and projecting outwardly therefrom is the jaw 8 that cooperates with

the stationary jaw 2, and teeth 9 are formed on the straight face of this jaw 8 for cooperation with the teeth 3 of the stationary jaw 2 in the manner well known in the art.

The inner side of this sleeve is formed with 55 the teeth 10 that are adapted for cooperation with the ratchet teeth 5 formed in the inner side edge of the shank 1 and the sleeve is of such width as to be capable of lateral sliding movement with respect to the shank so that 60 the teeth 10 will be free to move along the toothed edge of the shank without engagement of the teeth 5 as suggested in Figure 1 of the drawing.

For the purpose of moving the sleeve 6 65 outwardly whereby to lock the teeth 10 in engagement with the teeth 5 to secure the movable jaw 8 in any adjusted position with respect to the stationary jaw 2, I provide the elongated lever 11 which is pivoted at one 70 end to the inner end portion of the jaw member 2, as at 12.

The inner end portion of the stationary jaw member is preferably cut out to accommodate one end of the lever 11. The 75 lever extends through a substantially U-shaped bracket 13 that has its free ends embracing the respective sides of the intermediate portion of the shank 1 and rigidly secured thereto in any appropriate manner. 80 This U-shaped bracket is disposed at right angles with respect to the shank 1, and an expansible coil spring 14 is confined within this bracket for disposition between the adjacent edge portions of the shank and the 85 lever for normally urging the lever outwardly against the crown portion of the U-shaped bracket as clearly shown in Figures 1 and 3.

It is readily obvious that when the free end portion of the shank 1 which acts as a handle, 90 and the adjacent portion of the lever 11 are grasped, and said lever is pushed toward the shank against the tension of the spring 14, said lever will engage with the inner side of the sleeve and move the same outwardly 95 with respect to the shank 1 whereby to hold the teeth 10 in engagement with the teeth 5, thus securing the jaw member 8 in any vertically adjusted position with respect to the jaw 2.

It is thought from the foregoing description that the advantages and novel features of my invention will be readily apparent.

While I have shown the preferred embodiment of my invention, it is to be understood that minor changes in the size, shape and arrangement of parts may be resorted to without departing from the spirit of the invention and the scope of the appended claim.

Having thus described the invention, what I claim as new and desire to secure by Letters Patent is:—

In a wrench, the combination with a shank provided with ratchet teeth on the inner side edge thereof, a stationary jaw formed on one edge of the shank, a sleeve slidably mounted on the shank and having an opening of such size as to permit the same to move laterally with respect to the shank, a jaw formed on one end of the sleeve and extending laterally therefrom for cooperation with the stationary jaw, the intermediate portion of the sleeve being cut out at its outer side, teeth provided on the wall of the opening formed by the removal of a portion of the sleeve, an elongated lever pivoted at one end to the stationary jaw for disposition adjacent the inner side edge of the sleeve and adapted to engage the same to move the sleeve laterally whereby the teeth of the sleeve are brought into locking engagement with the teeth on the shank to secure the movable jaw against sliding movement.

In testimony whereof I affix my signature.

WARD MONTENEY.
